UNITED STATES PATENT OFFICE.

JOHN M. HOLT, OF GREENSBOROUGH, N. C., ASSIGNOR OF ONE-HALF TO
WM. B. FARRAR AND GEORGE S. SERGEANT, OF SAME PLACE.

INJECTOR FOR STEAM-BOILERS.

SPECIFICATION forming part of Letters Patent No. 243,560, dated June 28, 1881.

Application filed May 6, 1881. (No model.)

To all whom it may concern:

Be it known that I, JOHN M. HOLT, of Greens-
borough, in the county of Guilford and State of
North Carolina, have invented a new and use-
ful Improvement in Injectors for Steam-Boil-
ers; and I do hereby declare that the follow-
ing is a full, clear, and exact description there-
of, reference being had to the accompanying
drawings, forming part of this specification.

10 The object of my invention is to provide a
convenient means of indicating instantly to
the eye or ear the condition of the injector
when in operation, and at the same time to
utilize the water that escapes at the waste-
15 pipe of the injector for washing out the ash-
pan of the furnace.

In the accompanying drawings, Figure 1
represents a sectional view of an injector with
my improvements attached; Fig. 2, a detail
20 view; and Fig. 3, a side elevation of a loco-
motive, showing the connection of the waste-
pipe of an injector with the ash-pan.

As heretofore constructed, injectors for
steam-boilers have been without a convenient
25 means of indicating instantly any irregularity
of operation. It frequently happens, from one
cause or another, that the continuity of the jet
of water is broken before it reaches the de-
livery-tube, and, the check-valve consequently
30 becoming closed, the supply of water to the
boiler is shut off. In this event, for want of
proper suction, the water is no longer lifted
from the reservoir, and the steam collects in
the combining chamber or tube, and also in the
35 supply-pipe, so that in a very few moments
the parts become unduly heated and have to
be cooled before the normal action of the in-
jector can be restored. The only methods
heretofore used of determining such a condition
40 of the injector are by applying the hand to the
possibly heated portion, or by testing the
quantity of water in the boiler, both of which
require more or less time, during which the
heating of the said parts increases. It is evi-
45 dent, therefore, that if the irregularity should
be indicated instantly at its inception it could
be corrected in time to prevent the above-men-
tioned difficulty.

To accomplish this object I construct the

water-supply pipe A of the injector B with a 50
pipe, C, leading to the cab of a locomotive or
to any position occupied by an engineer. This
pipe C may be connected to the supply-pipe
at any desired position, the object being to
allow either water or steam to escape through 55
it when connection with the boiler through the
delivery-pipe is broken off. The free or outer
end of pipe C is provided with a suitable bell-
ringing valve to exclude the outer atmosphere,
and a cap for guiding the escaping water 60
downward into a receiver.

Any form of valve or any number of valves
desirable may be used, and for indicating the
escape of steam a suitable whistle may be com-
bined with the apparatus.

The injector being thus constructed, as soon
as the jet is broken and the suction necessary
to lift the water is discontinued the condens-
ation of the steam ceases, and its accumula-
tion in the combining-tube instantly forces the 70
water up tube or pipe C, by which it escapes
and at once gives the desired warning. The
irregularity may then be instantly corrected
by opening the valve of the waste-pipe P until
the flow of the water is renewed. As the 75
warning is given instantly upon the begin-
ning of the irregularity, and the latter may be
instantly corrected, the heating of the appara-
tus by the accumulation of steam is thus ef-
fectually prevented.

The waste-pipe P of the injector is provided
with a pipe, P', which extends to the ash-pan
of a locomotive or engine, for the purpose of
conducting the waste water thereto for extin-
guishing cinders and removing the ashes from 85
the pan. As usually constructed, the waste-
pipe is placed where the engineer can readily
see it, in order to ascertain whether the flow
of water is established before closing the valve
of the waste-pipe; but by my improvement 90
the use of this pipe as an indicator becomes
unnecessary, and it may therefore be used for
the purpose above mentioned, in addition to
its use for establishing the required flow or jet.

At any convenient position between the sig- 95
nal-valves and the injector a suitable cut-off
may be provided for use in case said valves
should need repairing.

Having thus described my invention, what I claim as new, and desire to secure by Letters Patent, is—

1. In combination with the water-supply pipe of an injector, the pipe C, leading to the engineer's cab, and having a suitable bell or whistle, substantially as shown and described, whereby the condition of the injector may be indicated instantly to the ear or eye, as set forth.

2. The combination, with the waste-pipe of an injector, of the pipe P', leading to the ash-pan of an engine, substantially as shown and described, whereby the waste water may be utilized for extinguishing cinders and removing ashes from the pan, as set forth.

J. M. HOLT.
